J. H. RIDINGS.

JAWED TOOL.

APPLICATION FILED APR. 9, 1921.

1,427,550.

Patented Aug. 29, 1922.

By

John Henry Ridings
Galt. Billman Attorney

UNITED STATES PATENT OFFICE.

JOHN HENRY RIDINGS, OF COAL CITY, ILLINOIS.

JAWED TOOL.

1,427,550.

Specification of Letters Patent. Patented Aug. 29, 1922.

Application filed April 9, 1921. Serial No. 459,906.

To all whom it may concern:

Be it known that I, JOHN HENRY RIDINGS, a citizen of the United States, residing at Coal City, in the county of Grundy and State of Illinois, have invented certain new and useful Improvements in Jawed Tools, of which the following is a specification.

My invention relates to improvements in jawed tools, such for example as pliers, 10 pinchers, tongs, and the like. The invention relates more particularly to improvements in the jaw portions of the tool through the provision of an improved pivoted or rocking jaw mounted upon and detachably secured 15 to one of the jaw members and adapted to cooperate with the opposed or toothed jaw and to rock upon its pivot or point of oscillation to conform to the form and plane 20 of the article being grasped and this independently of the particular position or angle of the opposing jaw of the tool.

The primary object of the invention is to provide a generally improved tool of this class which will not only be simple in construction, cheap of manufacture, and efficient in use, but one in which the jaws will more effectively conform to and grasp or hold an irregular or headed article such as a spike, bolt, or the like.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a side elevation of a tool constructed in accordance 40 with this invention.

Fig. 2, an edge view of the same.

Fig. 3, an edge view of one of the handled jaws, detached and illustrating the inner or toothed portion of the jaw.

Fig. 4, a similar view of the supplemental or opposed handled jaw member, the supplemental pivoted or rocking jaw being detached to illustrate the mounting therefor.

Fig. 5, a side elevation of the supplemental or rocking jaw detached.

Fig. 6, a view of the inner or toothed side thereof.

Fig. 7, a view of the outer or recessed bearing portion thereof and illustrating more particularly the transverse bearing

therefor for being seated on the bearing head or stationary portion of the main jaw.

Fig. 8, a fragmentary side elevation of the tool with the jaws and handles extended to their extreme open positions.

Fig. 9, an end view of the open or extended jaws, the tool being in a reversed position to that shown in Fig. 8 of the drawings.

Similar numerals of reference designate like parts throughout all the figures of the drawings.

In the drawings I have shown my improvements applied to or incorporated in a 70 jawed tool of the adjustable jaw plier type comprising, in the present instance, the usual pivoted members consisting of handles 1, pivotally connected by means of a pivot bolt or member 2, and terminating in jaws 75 1^a, and 1^b. The jaw and handle members are adapted to be adjusted to two positions by means of the shifting slot 1^c, terminating in bearing openings 1^d, and operating in a well known and understood manner.

As a means of enabling the jaw portions to conform to, and to more effectively grasp irregular shaped objects notwithstanding variations in the closed position of the main jaws, a supplemental pivoted or rocking jaw 85 3, is provided, said jaw comprising the spaced terminal members 3^a, adapted to span the toothed portion of the jaw 1^a, and to firmly engage with the inner and outer extremities thereof when the jaws are closed 90 against themselves as shown in Fig. 1, of the drawings.

As a means of providing a suitable space for the rocking jaw 3, as well as mounting the same in a convenient manner the jaw 1^b, 95 is provided with a cutaway portion or recess 3^b, on its inner side, said recess portion 3^b, being provided with a bearing portion 3^c, in the present instance, in its specific form of an inwardly extending bearing lug (see Fig. 100 4) said bearing portion 3^c, terminating at its inner end in a transversely extending bearing groove 3^d. The lug or bearing portion 3^c, is also provided with a transverse opening 3^e, preferably of elongated or arcuate form 105 as shown most clearly in Fig. 1 of the drawings.

As a means of detachably mounting the rocking jaw 3, upon the bearing portion or lug 3^c, and particularly as a means of relieving the attaching pin of any strain or stress, the rear side of the jaw 3, is provided with

an opening or recess 3^h, adapted to loosely receive the bearing portion 3^e, and to extend over the latter, said opening or recess terminating in a transversely extending bearing portion 3ⁱ, in the present instance, in the specific form of a bearing rib seated in the bearing groove 3^f, of the bearing lug.

As a means of removably mounting the jaw 3, upon the lug 3^e, and holding the parts 10 in proper assembled position an attaching pin, such as a bearing pin, screw, or the like, is transversely mounted in suitable openings in the sides of the jaw, said pin or attaching elements 4, extending through the arcuate 15 opening 3^c, so that as the jaw rocks or tilts on the bearing portion 3ⁱ, the attaching pin 4, will be moved to and fro in the arcuate opening 3^c. The jaw 3, has a limited rocking portion by reason of the rear portions 20 thereof forming stops coming into engagement with the adjacent inner sides of the jaw 1^b.

The base portions of the jaws 1^a, and 1^b, are provided with cutters 1^e, and 1^f, for cutting wire nails and the like.

The rocking jaw is provided with the toothed portions which are rounded in the center and provided with recesses 3^j, at the ends, said recesses being adapted to receive 30 the heads of articles such as nails, bolts, and the like, and as a means of holding such articles centrally the toothed portion of the rocking jaw 3, is preferably provided with centrally located recesses extending longitudinally in alignment as shown most clearly 35 in Figs. 6, and 9, of the drawings.

Having thus described one of the embodiments of my invention, what I claim and desire to secure by Letters Patent, is,—

40 1. A jawed tool, comprising pivotally con-

nected handled jaws, one of said jaws being spaced from the other and provided with a reduced bearing extending thereto, said reduced bearing being provided with a transverse recess at its end and a transverse opening, and a rocking jaw having an opening receiving said reduced portion and provided with a transverse fulcrum portion seated in said groove, and an attaching pin extending through said rocking jaw and said opening of said reduced bearing portion.

2. A jawed tool, comprising pivotally connected handled jaws, one of said jaws being recessed and spaced from the other and provided with a reduced bearing member extending therefrom, said reduced bearing member being provided with a transverse recess at its end and a transverse slot opening, and a rocking jaw having an opening receiving said reduced portion and provided with a transverse fulcrum portion seated in said groove, and an attaching pin extending through said rocking jaw and said opening of said reduced bearing portion.

3. In a jawed tool, a pair of pivotally connected handled jaws, one of said jaws being provided with gripping teeth and the other being spaced therefrom and provided with a bearing lug extending towards said first mentioned jaw, an auxiliary jaw having an opening at its rear receiving said bearing lug and supported solely on the latter, and an attaching pin carried by said auxiliary jaw and extending through said bearing lug and adapted to rock therein with the movements of said auxiliary jaw.

In testimony whereof I have affixed my signature.

JOHN HENRY RIDINGS.
